UNITED STATES PATENT OFFICE.

ARTHUR I. JACOBS, OF HARTFORD, CONNECTICUT, ASSIGNOR TO THE JACOBS MANUFACTURING COMPANY, A CORPORATION OF CONNECTICUT.

CHUCK.

1,123,541.

Specification of Letters Patent.

Patented Jan. 5, 1915.

Application filed September 19, 1912. Serial No. 721,114.

To all whom it may concern:

Be it known that I, ARTHUR I. JACOBS, a citizen of the United States, residing at Hartford, in the county of Hartford and State of Connecticut, have invented certain new and useful Improvements in Chucks, of which the following is a specification.

This invention relates to chucks, and while I do not restrict my invention to any particular type of chuck, it is of special utility when employed in connection with a sleeve chuck having forwardly converging jaws. I have made at least several distinct improvements in chucks of this class. First, the provision of a simple means by which the jaws may be adjusted more rapidly toward or from each other, than is possible with any other existing chuck of this type. Second, the provision of effective anti-friction means whereby the maximum efficiency of the jaws will be attained with a minimum amount of applied force, and at the same time prevent the possibility of the balls, or equivalent devices getting into the jaw receiving channels.

In the drawing accompanying and forming part of the present specification I have shown in detail one convenient form of embodiment of the invention, which to enable those skilled in the art to practice said invention will be set forth fully in the following description, while the novelty of the invention will be included in the claims succeeding said description. From this it will be evident that I do not restrict myself to the disclosure made by said drawings and description; I may depart therefrom in several respects within the scope of the invention included in said claims.

Referring to said drawings: Figure 1 is a side elevation of a chuck involving my invention. Fig. 2 is a sectional view of the same, and Fig. 3 is a developed view of the jaw actuating nut.

Like characters refer to like parts throughout the several figures.

The body of the chuck is designated by 5, and is preferably of casehardened steel, having the usual socket 6 serving the customary function. Said body has exteriorly thereof several forwardly-converging channels 7 in which are fitted for longitudinal sliding movement the jaws 8. Surrounding the said jaws is a split nut 9 fitted within

and rigidly connected with the sleeve 10, 55 rotatively disposed in the channel 10' and immovable in the direction of its axis of rotation. The nut 9 is in threaded engagement with the jaws 8. It, therefore, follows that when the sleeve 10 is rotated in one direction, the nut 9 will be correspondingly turned and will move the jaws 8 forward and simultaneously, owing to the angular disposition of the channels or grooves 7, cause the jaws 8 to approach or advance, 65 and that on opposite movement of said sleeve, the jaws are caused to recede. The front edge of the sleeve 10 is shown equipped with teeth 11 adapted to be engaged by the bevel pinion 12 rigid with the key 13, the 70 inner or journal end of which is adapted for removable reception in one of the several openings 14 in the chuck body 5 forward of the sleeve 10.

The foregoing, except as to the casehardened body, is a brief description of a chuck of sleeve type, in which I have chosen to show my invention.

In a chuck of the character indicated it is necessary at times to adjust the jaws a 80 considerable distance either toward or from each other, for instance after the chuck has engaged a comparatively large sized piece of stock, drill or tool, it may be necessary for it to hold a much smaller piece 85 or for some other reasons, it may be required to move the jaws from probably the maximum span to the minimum or relatively so, and of course rapidity in effecting such action is of importance. I provide 90 means whereby the jaws can be very quickly adjusted, and this I secure by forming upon the nut 9 a multiple thread, and although this multiple thread may vary, it is shown as being of triple form, the three threads 95 being represented in Fig. 3 and being denoted by 15, 16 and 17 respectively. The threads on the jaws 8 are similarly formed or match those of the nut. While, as I indicate, a triple or three thread construction 100 is desirable, it is not imperatively necessary, the invention residing rather in a plurality of threads, by reason of which the rapid adjustment of the jaws can be assured. Preferably, therefore, the multiple of the threads of 105 said nut conforms to the number of jaws, by virtue of which interchangeability of said jaws is accomplished. For example,

in the illustration the jaws are three in number, and although the thread of the nut is triple it might be sextuple.

To reduce as much as possible friction I prefer to interpose between the jaw operating nut and the chuck body, an anti-friction device, which at the same time also presents an effective means for resisting the thrust of the nut, and consequently of the jaws. I do not claim broadly this particular feature, as the same is illustrated in my prior Patent No. 911,012 of January 26, 1909 to which reference may be had. Nor do I desire to limit myself to the use of balls or analogous means between the feed nut and the body, although as I indicate such a construction is advantageous in that easy action is insured.

The rear edge of the nut 9 has a substantially circular race 18, and in said race are fitted several balls 19 which also find a bearing against the wall 20 of the annular groove 10'. It will be observed that the groove 10' opens into the jaw receiving channels 7 and that the nut 9 or the wall of the race 18, overhangs the balls 19 to such an extent that when the jaws 8 are in their extreme forward positions or at a point forward of the rear surface of the nut 9, said overhanging portion of the nut will

act to prevent positively the balls rolling into the said channels 7.

What I claim is:

1. A chuck comprising a body having an annular groove between the ends thereof and also having forwardly-converging channels opening into said groove, jaws longitudinally slidable in said channels, a nut rotatively mounted in said groove and having a feed connection with said jaws, and anti-friction devices between the nut and the chuck body, said nut having means for preventing positively said anti-friction devices falling into said channels. 40

2. A chuck comprising a body having an annular groove between the ends thereof and also having forwardly-extending channels opening into said groove, jaws longitudinally slidable in said channels, a rotary nut in said groove and provided with a ball race, balls fitted in said race and bearing against the body, the wall of said race overhanging the balls to thereby prevent their entering said channels. 4. 50

In testimony whereof I affix my signature in presence of two witnesses.

ARTHUR I. JACOBS.
